[57] **CLAIM**

An ornamental design for an inline water filter.

DESCRIPTION

FIG. 1 is an isometric view of an inline water filter showing my new design;

FIG. 2 is an elevational view taken from one end thereof, the opposite end being a mirror image of the end shown; and

FIG. 3 is an elevational view taken from one side thereof, the other side being a mirror image of the side shown.

FIG. 1

FIG. 2

FIG. 3
